UNITED STATES PATENT OFFICE.

ALEXANDER PAUL WOOD, OF SCHENECTADY, NEW YORK, ASSIGNOR OF TWO-
SEVENTHS TO VENIE WOOD APPEL, OF NEW YORK, N. Y.

COLLAPSIBLE TUBE.

Application filed November 6, 1925 Serial No. 67,220.

This invention relates to containers for viscous substances such as tooth paste, vaseline, grease etc.

- 5 The principal object of the invention is the production of a tube or container provided with an outlet opening whereby the contents of the tube may be extruded, said tube also having a closure or valve which normally closes said outlet opening but 10 which is adapted to be automatically opened by the contents of the tube when pressure is applied to said contents and to automatically reclose said outlet opening when pressure is released.
- 15 The invention also has for its object the production of a capless tube whereby the cost of manufacture of the tube is decreased and the possibility of the loss of a cap when the tube is in use is obviated.
- 20 Other and further objects and advantages of the invention will appear from the accompanying description taken in connection with the annexed drawings.

The accompanying drawings illustrate a 25 practical embodiment of the invention in which:

Fig. 1 is a side elevation of a tube showing the invention applied thereto.

Fig. 2 is an enlarged side elevation (partly 30 in section) of the upper portion of the tube showing some of the contents being extruded.

Fig. 3 is an enlarged top plan view (partly broken away) of the tube.

Although the invention is not to be so 35 limited I prefer to use it in conjunction with a collapsible tube of soft metal such as is now usually used for tooth paste.

Referring in detail to the several figures 40 of the drawings:

- 40 1 indicates the body of the tube, 2 the head thereof, 3 the neck which is integral with said head and 4 the top wall of the neck which may be secured to said neck in any desirable manner. Said top wall 4 is provided 45 with an annular outlet opening 5 as illustrated, the base of which forms a valve seat preferably having a relatively pointed engagement surface for the purpose set forth below.
- 50 The head 2 is provided with a chamber 6 inwardly of the opening 5 for receiving a compression spring 7 on which is seated a closure member shown in the present instance as a ball 8 preferably of metal which 55 extends within the chamber 6 and also

against the valve seat of the outlet opening 5 to normally close the same. The closure 8 is provided with an outwardly facing engagement surface extending from the portion thereof contacting with the opening 5 to the point of engagement thereof with the chamber wall 6. The head 2 is also provided with one or more passageways 9 preferably equidistantly spaced apart and preferably four in number. These passageways 60 communicate with the interior of the body 1 and with a space in the upper inner portion of the neck 3 so that communication may be had with the outlet opening 5 when the ball 8 is pressed inwardly against the action of the spring 7 as shown in Fig. 2.

Assuming the body of the tube to be filled with a viscous substance such as grease or tooth paste, the contents of the tube may be extruded by merely applying pressure to 75 said body as ordinarily, whereupon the contents will be forced outwardly in the tube through the passageways 9 and will contact with the engagement surface of the ball 8 forcing the latter inwardly within the chamber 6 against the action of the spring 7. The contents will then be extruded through the outlet opening 5 in an obvious manner. As soon as pressure is released from the body of the tube the action of the spring 7 again forces the ball 8 up into the opening 5 to effectively close said outlet opening, this action being facilitated by reason of the relatively pointed edge of the valve seat 80 formed on the opening 5.

It will be noted that because of the particular construction of the device, the contents thereof is extruded in the form of a hollow tube as shown at 10 in Fig. 2 thereby facilitating the spreading thereof on any 95 suitable object such as a tooth brush. It will be further understood that the invention is not limited to a device in which the tube itself must be compressed to extrude the contents as in some cases I propose to 100 employ a tube of hard metal provided with a piston or screw or similar device in its base which engages the contents directly and in which case the contents is extruded by pressure applied directly thereagainst, the 105 action of the valve being the same.

It will be further understood that various modifications may be resorted to without departing from the spirit of the invention as set forth in the appended claim.

What I claim as my invention is:—
A tube provided with an outlet opening,
said tube being also provided with a chamber
therein and with a passageway forming
5 communication between the interior of said
tube and said outlet opening, a spring in
said chamber and a ball engaged by said
spring and movable into or out of said
chamber, said ball normally closing said
10 outlet opening under the influence of said

spring, said ball being positioned in said
chamber and extending into said passageway
and being thereby subject to the influence
of pressure of the contents of said tube
therein for moving said ball away from said
outlet opening and into said chamber. 15

Signed at Schenectady in the county of
Schenectady and State of New York this
28th day of Oct., A. D. 1925.

ALEXANDER PAUL WOOD.
